(57) **CLAIM**

I claim the ornamental design for a lighting fixture, as shown and described.

DESCRIPTION

FIG. 1 is a perspective view of a lighting fixture showing a first embodiment of the new design. This fixture has mirror image symmetry about a vertical imaginary plane that bisects the canopy. The lantern glass, cap, base, and support rods each have a circular horizontal cross-section. The canopy has a circular vertical cross-section.

FIG. 2 is a front elevation view of the lighting fixture of FIG. 1.

FIG. 3 is a right side elevation view of the lighting fixture of FIG. 1, the left side elevation view being a mirror image of the right side.

FIG. 4 is a perspective view of a lighting fixture showing a second embodiment of the new design. This fixture has mirror image symmetry about a vertical imaginary plane that bisects the canopy. The lantern glass, cap, base, and support rods each have a circular horizontal cross-section. The canopy has a circular vertical cross-section.

FIG. 5 is a front elevation view of the lighting fixture of FIG. 4.

FIG. 6 is a right side elevation view of the lighting fixture of FIG. 4, the left side elevation view being a mirror image of the right side.

FIG. 7 is a perspective view of a lighting fixture showing a third embodiment of the new design. This fixture has mirror image symmetry about a vertical imaginary plane that bisects the canopy. The lantern glass, cap, base, and support rods each have a circular horizontal cross-section. The canopy has a circular vertical cross-section.

FIG. 8 is a front elevation view of the lighting fixture of FIG. 7.

FIG. 9 is a right side elevation view of the lighting fixture of FIG. 7, the left side elevation view being a mirror image of the right side.

FIG. 10 is a perspective view of a lighting fixture showing a fourth embodiment of the new design. Excluding the chain loops and hanging loop, this fixture has three-way, one

(Continued)

hundred twenty degree overall rotational symmetry. The canopy, lantern glass, cap, base, and support rods each have a circular horizontal cross-section.

FIG. 11 is a front elevation view of the lighting fixture of FIG. 10.

FIG. 12 is a perspective view of a lighting fixture showing a fifth embodiment of the new design. Excluding the hanging loop, this fixture has three-way, one hundred twenty degree overall rotational symmetry. The canopy, lantern glass, cap, base, and support rods each have a circular horizontal cross-section; and,

FIG. 13 is a front elevation view of the lighting fixture of FIG. 12.

The dashed lines on the drawings depict portions of the lighting fixture that form no part of the claimed design.
